UNITED STATES PATENT OFFICE.

ALLEN R. FOOTE, OF PHILADELPHIA, PENNSYLVANIA.

INHALER.

SPECIFICATION forming part of Letters Patent No. 355,309, dated January 4, 1887.

Application filed April 29, 1886. Serial No. 200,505. (No model.)

To all whom it may concern:

Be it known that I, ALLEN R. FOOTE, of Philadelphia, county of Philadelphia, and State of Pennsylvania, have invented a new and useful Improvement in Inhalers, of which the following is a full, clear, and exact description, reference being had to the accompanying drawings, making part of this specification.

My invention relates particularly to that class of inhalers used for volatile inhalants; and it consists in the combination, with a single receptacle, of several tubes, as hereinafter described, by which a single inhaler can be made to serve as an active inhaler when the patient draws the vapor into his own nostrils or throat, and as a passive inhaler by which the vapor is blown out by some one other than the patient. I attain these objects by the mechanism illustrated in the accompanying drawings, 20 in which—

Figures 1, 2, and 3 are tubes for active inhalation, Fig. 1 being a throat-tube, Fig. 2 a supply-tube to convey air near the bottom of the reservoir, and Fig. 3 a nasal tube. Figs. 4, 5, 25 and 6 are tubes for passive inhalation, 4 being the supply-tube, to which a hose with a bulb can be attached. 5 5 5 are tubes for directing the vapor to any required point. 6 is one particularly designed for use in diphtheria. Fig. 7 shows the receptacle or bottle furnished with stopper, with perforations to admit any one of the above-mentioned tubes at will. A sponge is carried by a bent wire and attached to the underside of the cork. Fig. 8 shows the bottle 30 provided with the nasal tube and the air-supply tube extended to pass the air through the contents of the bottle. Fig. 9 shows the bottle provided with active-inhalation tube and being used. Fig. 10 shows the same bottle fitted 35 with the interchangeable tube for passive inhalation.

It is not claimed that either of these methods of inhalation is new, or that, separately considered, the tubes are new; but with all the old 45 devices known up to the time of this invention different instruments have to be bought for the different sorts of application in active and passive inhalation.

By my invention all the different tubes 50 needed are furnished of the same size, so that they are interchangeable, and any and all fit

either of the openings in the stopper of the receptacle.

For reproducing the nascent chloride of ammonium, the receptacle or bottle is supplied 55 with a table-spoonful of muriatic acid, (preferably chemically pure,) and the sponge is soaked in aqua-ammonium, F F F.

For active throat-inhalation, the bottle is fitted with either the tube shown in Fig. 1, 60 alone, in which the air merely passes over the acid and the ammonium, or with tubes 1 and 2, both, in which case the air is drawn down through the acid before it passes the ammonium-sponge.

For passive throat-inhalation, the bottle is to be used either with tube 1 alone and with 1 and 5, or with tubes 4 and 5, the former being coupled by a short hose to the usual rubber air-forcing bulb. In the latter case the air is 70 forced downward past the ammonium sponge and through the acid before being driven out of the end of tube 5. The bent exit-tubes 5 give direction to the current. It may also be coupled with a short hose, at the end of which is a duplicate of tube 5. This latter form is particularly adapted for use in diphtheria, when it is not desirable that the nurse should come in close contact with the patient. The end of tube 5 could be made, of course, to enter the mouth 80 or nostril of the patient; but this is not needed, as the air soon becomes filled with clouds of crystals of nascent chloride of ammonium.

For use with menthol, a dram of menthol-crystals can be put dry into the reservoir of 85 the inhaler and two ounces of water at 70° to 80° Fahrenheit added. It will then be ready for active inhalation or passive with the proper tubes.

Tubes Nos. 1 and 4 can also be utilized for drinking-tubes.

The stopper of the inhaler-bottle is made of wood coated with an acid-proof enamel.

The uses to which the bottle, with its six different sorts of tubes, may be applied are only limited by the inventive genius of the physician. 95 With the present apparatus all the treatments can be readily made which formerly required the purchase of several complete instruments, and thus not only expense but space is economized, and also time in preparing and 100 charging different instruments as they become necessary at different stages of a treatment.

With the set of tubes described, used singly or in different combinations, all currents of air can be produced and controlled that can be used in active (throat or nasal) or passive inhalation. Further, the air-currents can be made to pass over or through the contents of the vessel or reservoir, thus adapting the apparatus to be used with any volatile inhalant.

What I claim as new, and desire to protect by Letters Patent, is—

1. The inhaler-vessel with the double-ori-ficed cork or stopper, combined with the set of tubes 1, 2, 3, 4, 5, and 6, all as and for the purpose described.

2. The inhaler-vessel, combined with the per-forated wooden cork coated with acid-proof enamel and carrying the sponge and tubes, all substantially as and for the purpose specified.

3. The double-ori-ficed enameled acid-proof cork or stopper, combined with the inhaling vessel and tubes, substantially as and for the purpose specified.

In testimony whereof I have hereunto set my hand this 28th day of April, A. D. 1886.

ALLEN R. FOOTE.
